UNITED STATES PATENT OFFICE.

ALFRED L. WELSH, OF KOKOMO, INDIANA, ASSIGNOR OF ONE-HALF TO CHARLES E. JOHNS AND B. FRED MILLER, BOTH OF KOKOMO, INDIANA.

BOTTLE HOLDER.

Application filed August 17, 1921. Serial No. 493,053.

To all whom it may concern:

Be it known that I, ALFRED L. WELSH, a citizen of the United States, residing at Kokomo, in the county of Howard and State 5 of Indiana, have invented a new and useful 10 Bottle Holder, of which the following is a specification.

This invention relates to a bottle holder especially designed for use in holding milk 15 bottles, means being provided whereby in order to permit the proper placing of the filled bottle in the holder, it is necessary for the customer to deposit in the holder an empty bottle which will be delivered to the 20 dealer when he opens the holder for the purpose of placing a filled bottle in position.

Another object is to provide a holder 25 which will completely house the bottle or bottles so as to protect them from dust and moisture.

A still further object is to provide a 30 holder in which the inserted bottle acts as a key for the purpose of permitting the unlocking of the door of an adjacent compartment to permit the opening of said door and the insertion of another bottle.

With the foregoing and other objects in view which will appear as the description 35 proceeds, the invention resides in the combination and arrangement of parts and in the details of construction hereinafter described and claimed, it being understood that, within the scope of what is claimed, 40 changes in the precise embodiment of the invention shown can be made without departing from the spirit of the invention.

In the accompanying drawings the preferred form of the invention has been shown.

45 In said drawings

Figure 1 is a horizontal section through the upper portion of the bottle holder, said section being taken on the line 1—1, Figure 2.

45 Figure 2 is a section on line 2—2, Figure 1.

Figure 3 is a section on line 3—3, Figure 1.

50 Figure 4 is a vertical transverse section through the slide bar showing adjacent parts of its elevating means in elevation.

Referring to the figures by characters of reference 1 designates a housing or casing

having an upstanding central strip 2 providing the front of the housing into two 55 parts each of which is formed with a door 3 hinged to one side of the strip 2 and having a knob 4 whereby the door can be readily swung into or out of closed position. Suitable stops indicated at 5 are arranged with 60 in the housing for limiting the inward swinging of the doors.

Secured to the lower surface of the top of the housing is a strip 6 having spaced depending portions 7 forming brackets and 65 supported by each of these brackets is a pivot screw 8 or the like on which a yoke 9 is pivotally mounted. The two yokes are arranged in the same plane, the inner portions of the yokes being rounded or formed 70 with their edges concentric with the pivots 8 so that said edges have a rolling contact when the yokes are swung about their pivots. The arms 10 of the yokes are extended normally backwardly from the doors 3 and 75 when the arms are thus located slots 11 which are formed in the rounded meeting edges of the yokes register as shown in Figure 1. Links 12 connect the doors to the respective yokes so that each door and its 80 yoke will move together. In other words when one of the doors is swung open, its yoke, if unlocked, will swing forwardly so that the arms 10 of the yoke will project through the door opening. When the door 85 is closed, however, the arms will be swung back into the housing as shown in Figure 1.

A rock shaft 13 is journaled in the housing and extends from the back to the front thereof and under the meeting portions of 90 the yokes. Fixedly secured to this rock shaft and extending upwardly therefrom is a finger 14 constituting a key adapted to be seated in either or both of the slots 11.

Extending forwardly from the back of 95 the housing 1 are brackets 15 having slots 16 therein and slidably within these brackets is a bar 17 provided near each end with a notch 18 in the upper edge thereof. Secured to the top of the housing near the 100 front thereof are spring latches or strips 19 which are preferably bowed as shown in Figure 3, the back ends of one of these strips being seated normally in a notch 18 so as thus to hold the bar 17 against sliding movement. A crank arm 20 is secured

to the rock shaft 13 and has a finger 20' which pivotally engages the middle portion of the bar 17 so that this bar cannot move unless the shaft 13 is rotated, or vice versa.

5 The forward end of the shaft 13 is provided with a handle or knob 21 which can be operated readily by a person adjacent the holder.

When the handle 21 is extended downwardly vertically the finger 14 is seated in both notches or slots 11 and it is thus impossible to rotate either of the yokes 9. Assuming that the yokes are empty, one latch strip 19 will be seated in a notch 18 so that the bar 17 cannot be shifted longitudinally. When the bar 17 is thus located the finger 14 is seated in only one of the slots 11 and, consequently, that yoke 9 under the strip 19 which is seated in a notch 18 is free to swing when its door 3 is pulled outwardly. After this one door has thus been opened a milk bottle, such as shown at B is placed on the arms of the exposed yoke and the door is then closed. This will cause the upper end of the supported bottle to wedge under and raise the strip 19 which is seated in the notch 18 so that the bar 17 will thus be released. At the same time the two slots 11 will again be brought into register. The shaft 13 can then be rotated to swing the finger 14 into the slot 11 in the yoke supporting the bottle and this movement will be sufficient to cause crank arm 20 to slide the bar 17 so as to bring the other notch 18 in position under the spring strip 19 above the empty yoke. Thus while the filled yoke cannot be shifted or its door opened because of the finger 14 being seated in the slot 11 of said yoke the other yoke 9 can be swung open and a filled bottle placed therein. Until this filled bottle is placed in position the empty bottle previously positioned in the holder as described cannot be removed. After the filled bottle has been placed in position its yoke is swung back by closing the door thereof and the top of the filled bottle will thus lift the spring strip 19 thereabove out of engagement with its notch 18. Consequently the bar 17 is released and shaft 13 can be rotated so as to swing the finger 14 out of the slot 11 in the yoke supporting the empty jar whereupon the door connected to said yoke can be swung open and the yoke moved to position where the empty jar can be removed therefrom.

Obviously this construction insures an interchange of bottles, it being impossible to

remove an empty bottle until after another bottle has been placed in proper position 60 within the holder.

What is claimed is:—

1. The combination with a housing, separate doors movably mounted thereon, and separate bottle supporting yokes movably 65 mounted in the housing and connected to the respective doors, said yokes having slots adapted to register when the doors are closed, of a controlling finger shiftable to position within either or both of the slots 70 to lock either or both of the doors against movement when shut, a slide bar movable by and with the shaft, and separate means for separately engaging the bar to hold said bar and the shaft against rotation, said 75 means being shiftable by bottles supported on the yokes and movable into the housing, to release the bar.

2. The combination with a housing, separate doors, separate bottle supporting yokes 80 within the housing and movable with the respective doors, said yokes having slots adapted to register when the doors are shut, of means movable into either or both of the slots for holding either or both of the yokes 85 and their doors against movement when the doors are shut, means for automatically locking one of the yokes and doors against movement when the doors are shut, and means operated by the placing of a bottle in the 90 yoke of the other door and the movement of said bottle into the housing for releasing the locked door to permit the opening thereof.

3. The combination with a housing, separate doors movably connected thereto and yokes within the housing and movable with the respective doors, said yokes constituting bottle supporting means, of an operating member, means movable therewith for holding either of the yokes against rotation when the doors are shut, a slidable bar movable in said member and having separate notches, separate spring members adapted to be seated within the respective notches alternately, said members being mounted in position to be engaged and shifted out of bar engaging positions by bottles supported by the yokes.

In testimony that I claim the foregoing 110 as my own, I have hereto affixed my signature in the presence of two witnesses.

ALFRED L. WELSH.
